UNITED STATES PATENT OFFICE.

ALBERT E. ROSE, OF BROOKLYN, NEW YORK.

COVERED PEN, PENCIL, &c.

No. 798,749.

Specification of Letters Patent.

Patented Sept. 5, 1905.

Application filed December 16, 1904. Serial No. 237,050.

To all whom it may concern:

Be it known that I, ALBERT E. ROSE, a citizen of the United States, residing at 363 Fulton street, Brooklyn, in the county of 5 Kings and State of New York, have invented a new and useful Improvement in Covered Pens, Pencils, &c., of which the following is a specification.

This invention is designed to obviate many 10 of the inconveniences and annoyances incident to the use of pens, (ordinary or fountain pens,) pencils, and articles of like nature. Among the defects of such manually-operative instruments are those due to the smoothness 15 and hardness of the surface grasped by the hand, which oftentimes causes the instrument to slip in the fingers and prevents it from being held safely in place when slipped behind the ear of the user, in cold weather 20 also the fingers having difficulty in grasping the instrument. The present invention contemplates the elimination of such defects and the provision of the article with a surface agreeable to the touch by combining there- 25 with a covering or coat of textile or knitted fabric fitting over the body portion of the instrument.

The present article of manufacture therefore embraces a pen, pencil, or analogous 30 manually-operative instrument having that portion adapted to be grasped by the fingers covered with a more or less tightly fitting tube of textile or knitted fabric. I do not deem it essential that either end of such tube 35 should be fixed to the corresponding end of the article; but ordinarily one or both ends are so fixed.

In the drawings accompanying the present 40 specification, Figure 1 is an elevation of a penholder embodying my present improvements. Fig. 2 is a view similar to Fig. 1, the keepers or ferrules at the ends of the article being omitted to show the tube ends closed over the ends of the body portion and 45 part of the tube-coat being broken away. Fig. 3 is an elevation of a pencil, showing one end of the tube-coat secured by a ferrule or a keeper to the pencil, the other end of the tube-coat being loose.

50 Similar characters of reference designate corresponding parts in all the figures.

The present invention is applicable generally to the class of articles hereinbefore men-

tioned and whether the penholder, pencil, &c., be circular in cross-section or angular 55 or whether it be cylindrical or tapering longitudinally.

In carrying the present improvements into effect the article of manufacture, whether it 60 comprises a penholder, such as that designated by 2, or a pencil, such as that designated by 3, is fitted with a coat or enveloping tube 4 of textile or woven fabric. Thus provided the article can be readily grasped by the fingers of the hand, presenting thereto a 65 soft yielding surface agreeable to the touch and not likely to slip. Tube lengths of proper dimension may be cut from a tubular fabric having a diameter, preferably, that will enable it to fit snugly over the body of the penholder, pencil, &c. If a tube length is used as a covering for a penholder, the longitudinally-taut length may be held in place by first tying the ends of the tube together at the ends of the holder, as indicated in Fig. 2, 70 after which the end ferrules or keepers 5 5' may be slipped over and fastened in place. Keeper 5 here constitutes the pen-point socket. In the case of a pencil-covering one end may only be secured in place by a keeper 75 5", (here constituting a rubber-holding attachment.) The other end of the tube length is left free, permitting the reduction of the length of the pencil in sharpening. If desired, both ends of the tubular fabric may be 80 left free.

Some of the advantages of the present invention have already been referred to. Among others may be mentioned that of preventing the accidental slipping of the pencil, &c., from 85 the pocket.

Having described my invention, I claim—

1. As a new article of manufacture, an article of the class described over which is fitted a length of a tube of woven or knitted 95 textile fabric, said tube being of substantially the same diameter as that of the article.
2. As a new article of manufacture, an article of the class described over which is fitted a length of a tube of woven or knitted 100 textile fabric, said tube being of substantially the same diameter as that of the article, combined with means for securing the tube length to the article.
3. As a new article of manufacture, an ar- 105

ticle of the class described over which is fitted a length of a tube of woven or knitted textile fabric of substantially the same diameter as that of the article and one of whose ends is compressed by a binding-string combined with a ferrule securing the tube length at the end to the article.

In testimony whereof I have signed my name to this specification in the presence of two subscribing witnesses.

ALBERT E. ROSE.
